US00D451904B1

(12) **United States Design Patent** (10) Patent No.: **US D451,904 S**
Bauman (45) Date of Patent: ** Dec. 11, 2001

(54) **WIRELESS COMPONENT**

(75) Inventor: **Stuart P. Bauman**, Skokie, IL (US)

(73) Assignee: **Shure Incorporated**, Evanston, IL (US)

(**) Term: **14 Years**

(21) Appl. No.: **29/113,424**

(22) Filed: **Nov. 4, 1999**

(51) LOC (7) Cl. **14-99**

(52) U.S. Cl. **D14/217**; D14/188

(58) **Field of Search** D13/184; D14/155,
D14/188, 189, 193-198, 217, 225, 226,
229; 455/90, 92, 100, 344, 347, 350, 351

(57) **CLAIM**

The ornamental design for a wireless component, as shown and described.

DESCRIPTION

FIG. 1 is a lower isometric view of the wireless component showing my new design;

FIG. 2 is an upper isometric view thereof;

FIG. 3 is a side view thereof, the opposite side being a mirror image.

FIG. 4 is a lower end view thereof;

FIG. 5 is an upper end view thereof;

FIG. 6 is a front view thereof; and,

FIG. 7 is a back view thereof.
